[57] CLAIM

The ornamental design for a direct station selection console, substantially as shown and described.

DESCRIPTION

FIG. 1 is a front isometric view of a first embodiment of the direct station selection console of this invention; FIG. 2 is a plan view on an enlarged scale of the top of the direct station selection console of FIG. 1;

FIG. 3 is a front elevation on an enlarged scale of the direct station selection console of FIG. 1;

FIG. 4 is a front isometric view of a second embodiment of the direct station selection console of this invention;

FIG. 5 is a plan view on an enlarged scale of the top of the direct station selection console of FIG. 4;

FIG. 6 is a front elevation on an enlarged scale of the direct station selection console of FIG. 4;

FIG. 7 is a right side elevation on an enlarged scale of the direct station selection consoles of FIGS. 1-3 and FIGS. 4-6;

FIG. 8 is a left side elevation on an enlarged scale of the direct station selection consoles of FIGS. 1-3 and FIGS. 4-6;

FIG. 9 is a back elevation on an enlarged scale of the direct station selection consoles of FIGS. 1-3 and FIGS. 4-6; and

FIG. 10 is a view on an enlarged scale of the bottom of the direct station selection consoles of FIGS. 1-3 and FIGS. 4-6.
